UNITED STATES PATENT OFFICE.

HENRY J. VOGEL, OF BROOKLYN, NEW YORK, ASSIGNOR TO WILLIAM VOGEL & BROTHERS, OF SAME PLACE.

FILLER AND FAUCET FOR CANS.

SPECIFICATION forming part of Letters Patent No. 341,783, dated May 11, 1886.

Application filed March 18, 1886. Serial No. 195,703. (No model.)

To all whom it may concern:

Be it known that I, HENRY J. VOGEL, a citizen of the United States of America, residing at Brooklyn, in the county of Kings, in the State of New York, have invented a new and useful Filler and Faucet for Cans, of which the following is a specification.

My invention has relation to improvements in fillers and faucets to be applied to cans and to other metallic vessels which are generally returned to the seller by the consumer after being emptied of their liquid contents and then refilled by the manufacturer or factor. This usage of the trade makes it requisite that the vessels should have a "filler and faucet" which combines in its construction the elements common to both separately—that is, convenient means by which the contents may be supplied to the can, and convenient means by which the can may be discharged of its contents.

It is the object of my invention to provide a combined filler and faucet which is durable and cheap in construction, readily applied, certain in operation, either as a means for filling or discharging the contents or for sealing the can against the escape of the liquid.

With these purposes in view my invention consists in a filler and faucet comprised of a can-plate, a cylindrical shell or body fixed thereto provided with coincident exterior and interior screw-threads, and a discharge pipe or nozzle leading therefrom; a screw-threaded cap to set over and screw on the exterior threads of the body and formed with a central aperture; a screw-threaded valve consisting of a cylindrical shell with closed top, and having threads fitted to the interior threads of the body, and a stem, as hereinafter will be fully described, and as will be specifically and clearly pointed out in the claims made hereto, as required by the statute.

I have fully illustrated my improved device in the accompanying drawings, forming a part of this instrument, wherein Figure 1 is a perspective view of the device. Fig. 2 is a central vertical sectional view showing the foot of the valve-shell down on the packing and the device closed; and Fig. 3 is a similar view showing the valve open.

In the last two figures the materials are shown thicker than used in the manufactured

article, in order that the parts may be the better defined and shown.

Reference being had to the drawings, the numeral 1 designates the can-plate, made of the usual pattern, consisting of a circular plate of sheet metal having a rim-flange struck downward to set in the annular groove pressed in the top of the can, and having the center cut out to form the aperture 2, through which the contents are injected and discharged.

The numeral 3 designates the body or shell which receives the retaining-cap and the valve, the flange at its base also forming the seat of the valve. This body 3 consists of a seamless piece of sheet metal having an aperture, 4, in one side at the base, over which the mouth of the discharge pipe 5 is secured by any well-known means. This body 3 is formed with screw-threads 6, so impressed that they shall serve to take the cap on the outside and to receive the valve on the inner side. The threads are preferably made of double pitch to hasten the travel of the valve when moved. The metal of the body at the base is struck in at right angles to the walls thereof, forming an inwardly turned annular flange, 7, which serves as the seat for the packing 8, which is impressed by the edges of the valve when screwed down, as shown in Fig. 2 of the drawings. The foot of the valve may set directly on the metal of the body, but a packing gives additional security. The edge of the flange or valve-seat is turned back, as seen at *a*, under the can-plate to give the body a substantial connection with the can-plate. Additional rigidity is attained by soldering the parts in this connection. I thus attain the very best connection of these parts, one which is proof against leaks, and which is as strong as the body of the metal can give.

The numeral 9 designates the cap. This consists of a seamless piece of sheet metal, having screw-threads 10 to fit over the threads of the body, having the upper edge struck down, forming a flat flange, 11, and having an aperture in the plate, which is somewhat larger than the stem of the valve which passes through it.

The numeral 12 designates the valve struck from a single piece of sheet metal and formed with a valve portion, 13, threaded to fit the interior threads in the body, a stem, 14, of less

diameter than the valve-shell, and a finger-piece on the top. The shoulder 15, between the threaded end and the stem, sets against the under face of the cap when the valve is drawn 5 up and stops all leaks at this point; but, if desirable, a ring of packing may be fitted under the flange of the cap, and thus all tendency to leak be effectually stopped.

It will be perceived from the description 10 that by removing the cap the valve may be removed, when the can may be filled, and that after filling is accomplished the cap may be replaced and the valve screwed home, when a tight and safe joint is obtained. By making 15 the valve-shell to fill the interior of the body and with closed upper end I lessen the chances of dripping when the valve is drawn up and the liquid is poured through the nozzle, this because the fluid cannot escape between the 20 walls of the valve and the body to above the shell of the valve to drip from around the stem.

What I claim as my invention, and desire 25 to secure by Letters Patent, is—

1. A filler and faucet composed of the following elements: a can-plate having an opening therein, a cylindrical sheet-metal body secured to the can-plate and having coincident outer and inner screw-threads, and an inwardly-

turned annular flange at its lower end provided with a packing-ring, a discharge-pipe 30 secured to the body, a sheet-metal cap adapted to screw down on the exterior threads of the body and formed with a flat annular flange extended inward about its upper edge, and a valve formed with a threaded lower end to fit 35 the interior threads of the body, a stem to pass through the hole in the top of the cap, and a shoulder between the stem and the threaded end to set against the flange of the cap, substantially as described, and for the purpose 40 stated.

2. The combination, with the can-plate, of a filler and faucet, of a sheet-metal body provided with a discharge-pipe, a cap, and a valve, and formed with an inwardly-turned 45 annular flange at its base, and having the inner edge of said flange turned down and under the edge of the can-plate and secured thereto, substantially as described.

In witness whereof I have hereunto set my 50 hand in the presence of two attesting witnesses.

HENRY J. VOGEL.

Attest:

BENJ. F. SANBORN,
W. J. KENNEDY.
